(57) **CLAIM**

The ornamental design for a current transducer, as shown and described.

DESCRIPTION

FIG. 1 is a bottom front right perspective view of a current transducer showing my new design;

FIG. 2 is a top front right perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof; and,

FIG. 8 is a right side view thereof.

The broken lines in the figures show portions of the current transducer that form no part of the claimed design. Features within the broken lines form no part of the claim.

1 Claim, 8 Drawing Sheets
